LAUNDRY MACHINE SUPPORT

Thomas J. Little, Jr., Syracuse, N. Y., assignor to
Easy Washing Machine Corporation, Syracuse,
N. Y., a corporation of Delaware

Application July 9, 1937, Serial No. 152,799

4 Claims. (Cl. 211—71)

My invention relates to domestic laundry machines of the type wherein a washing vat and a drying vat are mounted in juxtaposition upon a common support.

5 An object of my invention is to provide a skirt structure, for hiding the driving mechanism of a laundry machine, which may be fabricated at a relatively small cost.

Another object of my invention is to provide a 10 relatively inexpensive supporting structure for the vats of a laundry machine and the driving mechanism therefor.

Another object of my invention is to provide a 15 strong rigid supporting structure for the vats and driving mechanism of a laundry machine.

A further object of my invention is to provide an improved method of bracing the legs of a laundry machine.

More specifically, my invention contemplates 20 the provision of a supporting structure for a laundry machine wherein the skirt, which underlies the vats of the machine, is formed by rolling two sheets of metal into substantially circular form, conforming in diameter to the diameter of 25 the respective vats, and forming bridge portions between the circular portions so that a skirt substantially continuous in appearance is provided and, in addition, my invention contemplates the provision of a web or support for the driving 30 mechanism carried by said skirt which not only serves to support the driving mechanism, but also serves rigidly to secure the separate elements of the skirt together.

Other objects and advantages of my invention 35 will be more apparent from the following description when taken in connection with the accompanying drawings, in which:

Figure 1 is a front elevation of a domestic laundry machine in which my novel skirt and 40 supporting structure is embodied.

Figure 2 is a sectional view taken on the line 2—2 of Figure 1.

Figure 3 is a view taken on the line 3—3 of 45 Figure 2.

Figure 4 is a view taken on the line 4—4 of Figure 3.

Figure 5 is a view taken on the line 5—5 of 50 Figure 2.

Figure 6 is a view taken on the line 6—6 of Figure 5.

Figure 7 is a view illustrating the manner in 55 which the legs are braced from the casing of the driving mechanism.

The laundry machine of my invention comprises a washing vat 11 having a suitable wash-

ing element mounted therein, such as an agitator, and a drying vat 12 having suitable means mounted therein for drying the clothes, such as a perforated rotatable basket.

In the past, two methods of supporting the 5 washing and drying vats have been quite generally employed. One of these is to provide a rigid base extending beneath both of the vats, the outer edges of which are turned downward to provide a depending skirt extending beneath 10 the vats for hiding the driving mechanism of the machine. The second method involves cutting circular openings in the base of the combined base and skirt structure of the first method, conforming in diameter substantially to that of the 15 diameter of the vats and supporting the vats on the upper edges of the openings thus formed. Either of these methods requires a rather expensive stamping and the use of a rather expensive machine to form the stamping. Moreover, the 20 cut out portions of the second method are wasted. In my invention, the skirt is formed by rolling two sheets or strips of metal into rolls conforming in diameter to the diameter of the vats and then utilizing bridging portions between the 25 independent rolls as a means of securing them together. The skirt thus provided is substantially unitary and continuous in appearance.

The skirt, generally indicated by the numeral 13, comprises a strip of steel 14 rolled so that 30 its diameter conforms substantially to the diameter of the washing vat with which it is to be used. At its top edge, as shown in Figure 5, the roll 14 is provided with a portion 16 of reduced diameter over the upper edge of which is fitted a U-shaped rubber ring 17 upon which the washing vat rests. The bottom of the vat is provided with a circular indenture or groove 18 which registers with the U-shaped rubber ring 17. The skirt portion for the washing vat thus formed presents a substantially continuous wall with the side walls of the washing vat, as will be apparent from Figure 1. The bottom of the roll 14 is rolled inward, as indicated at 19, for a purpose later to be described.

A second roll 21, formed in the same manner as the roll 14, is conformed in diameter to the diameter of the drying vat 12. A U-shaped rubber ring 22 is interposed between the upper edge of the roll and the lower edge of the drying vat.

To secure the two rolls together and also to bridge the gap between them, filler or bridging pieces 23 and 24 are provided. The filler pieces may be integral but preferably two separate pieces are used. The filler pieces are similar and the

50

55

method of securing them to the rolls is the same so that a description of one will suffice. The filler piece comprises a horizontal shelf portion 25 which closes the horizontal space inside of a line substantially tangent to both vats. A vertical portion 26, curved in cross section, as indicated in Figure 4, extends between the rolls 14 and 21 thus forming a substantially continuous skirt extending below and completely around both vats. The filler pieces may be secured to the rolls in any suitable manner, but I have devised a simple means of accomplishing this.

Portions of the rolls 14 and 21 are cut out to form flaps 27, as shown in Figures 3 and 4. These flaps are then bent and welded to the inner vertical wall of the filler piece. Additional portions, adjacent the top edges of the rolls 14 and 21, are cut out to form flaps 28 which are bent upward and welded to the underside of the filler piece. The filler pieces are thus secured to the rolls so that a substantially continuous rigid skirt assembly is formed.

As shown in Figure 3, the roll 14, at 29, is cut out to form an opening 31. A corresponding opening, indicated at 32 in Figure 2 and Figure 4, is provided in the roll 21. The openings in the rolls enable the driving mechanism for the machine to be mounted closely adjacent and extend between the bottoms of the vats. As indicated at 33, the roll 14 is provided with a second cut out portion to accommodate a supporting plate or channel bar 34. A cut out (not shown) for the channel is also provided in the roll 21. The channel 34 extends across the bottoms of both vats 35 and serves as a mounting support for the driving mechanism.

As shown in Figure 4, relatively narrow strips 36, constituting the ends of the roll 14, extend over the top of the channel 34 and these ends are secured together by welding a reinforcing strip 37 to them. The ends 38 of the roll 21 are similarly secured together by welding to them a reinforcing strip 39. As shown in Figures 3 and 4, portions 41 of the roll 21, and portions 42 of the roll 14, are bent so that they lie parallel to the sides 43 of the channel 34. Nut and bolt assemblies 44 are then provided to clamp together the sides of the channel and the bent portions 41 and 42 of the rolls so that the rolls are rigidly secured 50 to the channel.

The end of the channel 34, as indicated in Figure 2, is bent downward, at 46, and bolted or welded to a bracket 47. The sides 43 of the channel are also provided with lugs 48 which are bolted to the bracket 47. The bracket 47 has arms 49 which extend to the side walls of the roll 14 and are bent at 51 and bolted, as indicated at 52, to the roll 14 in such position that the projecting ends of the bolts may be covered 55 by the legs 53. The opposite end of the channel 34 has a turned down portion which is bolted, as indicated at 54, to the roll 21, the heads of the bolts being covered by the leg 56. A bracket 57, interposed between the downturned portion of 60 the channel and the roll 21, has inwardly extending arms 57' which are riveted to the side portions 43 of the channel 34. There is thus provided a skirt assembly which is, for all practical purposes, a rigid integral unit. The channel 34, 65 together with the brackets by which it is secured to the skirt, constitute a web for receiving the driving mechanism for the laundry machine. The web not only supports the driving mechanism, but serves to make more rigid the skirt assembly. The motor 58 and the gear casing 59

for housing the driving mechanism, which are indicated in dotted lines in Figure 2, may be supported from the web in any suitable manner not necessary to be shown or described herein. The channel 34 is provided with openings 61 for the drive shafts which extend upward into the washing and drying vats.

The legs 53 and the leg 56 are similar and are attached in a similar manner to the skirt 13 so that a description of one will suffice. The leg 53, as shown in Figure 5, is provided with a lug 62 which lies in a horizontally extending slot formed in the skirt. A pair of additional lugs 63 lie in a pair of vertically extending slots cut in the skirt. A bracket 64 is welded to the inside of the leg 15 for the reception of the head of a nut and bolt assembly 66. A spacer 67 is provided so that when the nut is drawn up tightly, the skirt will not be deformed. At 68, the inner edges of the legs, which engage the side walls of the skirt, are 20 curved outward to conform to the curvature of the lower edge of the side wall of the skirt so as to provide a seat on the leg for the skirt. At its lower end, as indicated in Figure 7, the side edges of the leg are extended and welded together at 69 25 so that the leg, at this point, is circular in cross section. Into the bottom of the legs may be fitted suitable casters 71.

To the lower end of the leg, by a nut and bolt assembly 72, a brace rod 73 is secured. The brace rod extends toward the center of the machine and is bolted, as indicated at 73', to a boss 74 depending from the bottom of the gear case 59. As indicated in Figure 1, each of the legs is independently braced and secured to the gear case. 35 In the washing machines of the prior art, it has been customary practice to extend the brace rods from the legs and join them together so that if the leg were bumped against a rigid object the strain would be transmitted through the brace 40 rods to all the legs. Consequently, if the machine were severely bumped, all of the legs would tend to bend or buckle in the same direction. In my construction, since each of the legs is independently braced against the gear case, which in turn 45 is rigidly tied to the web, there is little tendency, if one of the legs is heavily bumped against an object, for the other legs to be affected by the strain.

As shown in Figures 2 and 5, extending upward 50 from the interior of each of the legs is a tie rod 76, the upper end of which is threaded, as indicated at 77, into a fitting 78. The lower end of the tie rod is held in position on the bracket 64 by a nut 79 and the fitting 78 is tied to the side 55 walls of the vat by a nut and bolt assembly 81 which extends through the side wall of the vat. The tie rods thus serve to aid in retaining the vats in position on the skirt.

It will be apparent that I have provided a 60 rigid supporting structure for a laundry machine in which the skirt is made up of separate pieces welded together to provide a unitary skirt assembly and that the web not only serves to support the driving mechanism, but also aids in 65 making rigid the skirt assembly. A rigid unit of great strength is thus provided which may be fabricated at a reasonable cost. It will further be apparent that various changes and modifications may be made in the form and relation of 70 parts without departing from the spirit of my invention as set forth in the appended claims.

I claim:

1. A laundry machine support comprising a pair of substantially cylindrical members each 75

formed from a single strip of metal, said cylindrical members being arranged side by side and in contact with one another and being secured together adjacent a line between their axes, and 5 a pair of filler pieces one at each side of and lying between said cylindrical members and substantially bridging the spaces between the outer peripheral portions thereof so that the outer exposed sides of said cylindrical members and filler 10 pieces form a substantially continuous and smoothly contoured skirt.

2. A laundry machine support comprising a pair of substantially cylindrical members each formed from a single strip of metal, said cylindrical members being arranged side by side and in contact with one another and being provided 15 with mating integral lugs struck out from the walls thereof adjacent a line between their axes, said lugs being joined together to secure said 20 cylindrical members to each other, and a pair of filler pieces one at each side of and lying between said cylindrical members and substantially bridging the spaces between the outer peripheral portions thereof so that the outer exposed sides 25 of said cylindrical members and filler pieces form a substantially continuous and smoothly contoured skirt.

3. A laundry machine support comprising a pair of substantially cylindrical members each 30 formed from a single strip of metal, said cylind-

rical members being arranged side by side and in contact with one another and being secured together adjacent a line between their axes, and a reenforcing member passing through openings formed in said cylindrical members and below 5 the upper edges thereof and adjacent a line between the axes of said cylindrical members, said reenforcing member being secured to the walls of said cylindrical members at a plurality of points.

4. A laundry machine support comprising a 10 pair of substantially cylindrical members each formed from a single strip of sheet metal, said cylindrical members being arranged side by side and tangent to one another, a pair of filler pieces one at each side of the line of tangency of said 15 cylindrical members and secured to the latter and substantially bridging the spaces formed between the line of tangency of the cylindrical members and the outer peripheral portions thereof so that the outer exposed sides of said 20 cylindrical members and filler pieces form a substantially continuous and smoothly contoured skirt, and a channel member passing through openings formed in said cylindrical members and below the upper edges thereof and adjacent a 25 line between the axes of said cylindrical members, said channel member being secured to the walls of said cylindrical members at a plurality of points.

THOMAS J. LITTLE, JR. 30
